(No Model.)

P. DITTMAN.
WAGON TONGUE SUPPORT.

No. 550,748.

Patented Dec. 3, 1895.

Inventor:

By John H. Hutchins his Attorney.

UNITED STATES PATENT OFFICE.

PETER DITTMAN, OF MARSEILLES, ILLINOIS.

WAGON-TONGUE SUPPORT.

SPECIFICATION forming part of Letters Patent No. 550,748, dated December 3, 1895.

Application filed August 5, 1895. Serial No. 558,209. (No model.)

To all whom it may concern:

Be it known that I, PETER DITTMAN, a citizen of the United States of America, residing at Marseilles, in the county of La Salle and 5 State of Illinois, have invented certain new and useful Improvements in Wagon-Tongue Supports, of which the following is a specification, reference being had therein to the accompanying drawings and the letters of reference thereon, forming a part of this specification, in which—

Figure 1 is a perspective view of the tongue-support as it would appear attached to a wagon, and Fig. 2 is a side view of the lever 15 of the device for elevating and lowering the outer end of the wagon-tongue.

This invention relates to certain improvements in tongue-supports for wagon-tongues, which improvements are fully set forth and 20 explained in the following specification and claims.

Referring to the drawings, R represents the wagon-tongue to be supported, and A represents the front end-board of a wagon-box.

25 H represents a coil-spring having a short chain J attached to its outer end, and the outer end of said chain is attached to the wagon-tongue by means of a staple K. The inner end of said coil-spring has attached to 30 it a short chain P, having a clevis L attached to its inner end provided with a grooved roller G, adapted to travel laterally on a rail F, secured to the end-board A of a wagon-box.

B is a hooked lever forming a link in the 35 chain P. The inner hooked end of said lever is hooked into a link of said chain, while the arm of said lever passes through the next adjacent link in such manner as to slide therein from the position shown in Fig. 2 to that 40 shown in Fig. 1.

C is a short chain attached to the outer end of lever B B', having a hook D on its outer end, so that when the said lever is in the position shown in Fig. 1 said chain C may be 45 passed around the standard S on the upper edge of the end-board and hooked back upon itself, so as to give sufficient tension to the device and support the outer end of the tongue. A cord E is attached to the outer 50 end of chain C for the purpose of retaining control of said chain and its lever when the

said chain is released from standard S and the lever B let down to the position shown in Fig. 2, the driver retaining hold of said cord in order to pull up said lever to its first position. (Shown in Fig. 1.)

55 The lever B is formed so as to have a bend V near its outer end forming a hook to hook into the link on that end of the chain P, and the part of said lever between said bend V 60 and its outer end forms an extension B' of the lever for the purpose of obtaining greater purchase on the lever in order to raise it up to the position shown in Fig. 1. The said lever is thus used so as to relieve the tongue-support from supporting the outer end of the tongue when the wagon is not in use and when no team is attached to the wagon, in which case the lever is let down, as shown in Fig. 2, so that the outer end of the tongue will 65 rest on the ground; but when a team is attached and it is desirable to relieve the necks of the team from supporting the tongue the lever is turned up and secured to the position shown in Fig. 1, when the weight of the outer 70 end of the tongue is taken off the team and held by the tongue-support. The movement of the grooved roller on the said rail F permits lateral movement of the tongue in either direction. When the wagon is driven on a 75 dumping-platform at a warehouse to dump its load of grain, it is desirable to lengthen out the tongue-support by means of letting down said lever, so as to not lift the outer end of the tongue up too high at the time the rear end of the wagon is lowered in order to 80 dump its load.

Having thus described my invention, what I claim as new, and desire to secure by Letters Patent, is as follows:

90 1. The wagon tongue support comprising the combination of the coil spring H, chain J for connecting the outer end of said spring to the wagon tongue, chain P for connecting the inner end of said spring with a lever forming one of its link sections, and having the grooved roller G on its outer end opposite said spring, rail F secured to the end board of a wagon box, and adapted to carry said roller, hooked lever B B' having the hooked 95 bend V and forming a section or link of chain P, and having chain C attached to its outer 100

end, and the cord E forming a continuation of chain C all arranged to operate substantially as and for the purpose set forth.

2. A wagon tongue support comprising the combination of a coil spring having chains connected with each of its ends, and adapted to connect the wagon tongue with the front end board of a wagon, and a lever forming a section or link of one of said chains, and having its end connected with said chain formed

like a hook and having the extremity of its hooked end connected with a link of the chain, and having its free end passed through the opposite link of said chain and adapted to slide therein, substantially as and for the purpose set forth.

PETER DITTMAN.
